Primary Examiner — Kevin Rudzinski*Assistant Examiner* — Sean D Lough(74) *Attorney, Agent, or Firm* — James P. Muraff; Neal, Gerber & Eisenberg LLP(57) **CLAIM**

The ornamental design for a sensor cover, as shown and described.

DESCRIPTION

FIG. 1 is a front, left perspective view of the sensor cover in a closed position.

FIG. 2 is a left side plan view thereof.

FIG. 3 is a right side plan view thereof.

FIG. 4 is a front plan view thereof.

FIG. 5 is a rear plan view thereof.

FIG. 6 is a top plan view thereof; and,

FIG. 7 is a bottom plan view thereof.

The broken line showings of (a) the hood and (b) the holes or apertures are for the purpose of illustrating portions of the article and form no part of the claimed design.

1 Claim, 4 Drawing Sheets(56)
